UNITED STATES PATENT OFFICE.

SIMON COOPER, OF BROOKLYN, NEW YORK, ASSIGNOR TO SPEEDAUTOMATIC COMPANY,
A CORPORATION OF DELAWARE.

FEEDING MECHANISM.

Application filed June 29, 1920. Serial No. 392,759.

To all whom it may concern:

Be it known that I, SIMON COOPER, a citizen of the United States, residing at Brooklyn, in the county of Kings and State 5 of New York, have invented new and useful Improvements in Feeding Mechanism, of which the following is a full, clear, concise, and exact description, reference being had to the accompanying drawing, forming a 10 part of this specification.

My invention relates to improvements in feeding machines and the like, which are particularly adapted for the handling of newspapers, pamphlets, periodicals, magazines and similar articles, though my invention is not necessarily limited in its use to these specific articles.

By means of my present invention each article may be handled individually and delivered as such to another associated mechanism or machine, such as an addressing machine, with which a device embodying a 15 form of my invention may be working in conjunction.

One object of my present invention is to provide a feeding mechanism whereby the feeding of articles, as individual units, may be automatically effected without interruption, the articles being delivered in proximity to feeding rolls from a source of supply that is intermittently drawn upon by automatic means to supply a collection of such articles adjacent to said feeding rolls. The feeding rolls serve to automatically and 25 independently deliver the articles as individual units from the collection immediately adjacent to said feeding rolls. This collection is replenished with articles from the original source of supply by automatic means 30 cooperating with the feeding rolls so as to ensure a steady and continuous ejection of articles from my feeding mechanism to any other machine, such as a mailing machine, addressing machine, or a wrapping machine, 35 that may be associated with the feeding mechanism of my present invention.

My present invention embodies a feeding mechanism that serves to deliver the articles in question to various machines wherein it 40 may be desired or required to handle and manipulate the articles individually. The feeding rolls incorporated in the present embodiment of my feeding mechanism are adapted to operate continuously in order

that a steady supply of such articles may be 55 expeditiously ejected and submitted for subsequent handling without interruption.

The feeding rolls are automatically supplied with the individual articles which are delivered to them from a collection of such 60 articles that is disposed immediately adjacent to the feeding rolls. This collection of articles is maintained adequate at all times through the operation of automatic means which replenishes the collection adjacent to 65 the feeding rolls from a large source of supply of the articles.

While I mention feeding rolls in connection with the feeding mechanism of my present invention, it will be obvious from the 70 following description of my invention that feeding rolls are not essential as long as the accomplishing of the feeding operation, as explained above, is effected.

Another object of my invention is to provide a machine for automatically feeding newspapers, periodicals and the like which incorporates a conveyor mechanism that is intermittently operated in accordance with the size of the collection of articles that are 80 subject to immediate delivery as individual units to the feeding rolls. This conveyor mechanism is capable of handling the articles in bulk and of automatically delivering them to a location adjacent to the feeding rolls.

A further object of my invention is to provide means in a machine of the character indicated above whereby the articles delivered by the aforesaid conveyor mechanism are automatically stacked or arranged in a suitable pile immediately adjacent to the feeding rolls, the height of this pile or stack of articles serving to automatically regulate the intermittent operation of the 95 said conveyor mechanism.

A further object of my invention is to incorporate in a machine of this general type, means for automatically handling as individual units each of the articles comprised in the pile of articles immediately adjacent to the feeding rolls, this handling of each article, as a separate unit, being continually effected irrespective of the intermittent delivery of a plurality of such articles to this pile by the said conveyor mechanism.

A further object of my invention is to pro-

vide automatic means for tamping the pile or stack of articles immediately adjacent to the feeding rolls in order to maintain the pile in regular order and to preclude disarrangement of the articles comprised therein. This tamping operation is performed by means that does not hinder or oppose the individual handling of each separate article and the subsequent delivery thereof to the feeding rolls.

Another object of my invention is to provide a machine possessing the attributes stated above which will be simple and compact in construction, durable, effective and efficient in operation.

To the attainment of the foregoing objects and to the accomplishment of other new and useful objects, as will hereinafter appear, my invention consists in the features of novelty 20 in the construction, combination and arrangement of the mechanism hereinafter more fully described and shown in the accompanying drawings that illustrate a machine embodying a form of my invention, 25 and in which:

Fig. 1, is a side view in elevation of a machine constructed in accordance with my invention;

Fig. 2 is an enlarged view of a portion 30 of the mechanism of Fig. 1 and shows two successive positions, one in dotted lines and one in full lines, occupied by the members 35 and 39;

Fig. 3 is a view in elevation and transversely of the view of Fig. 1 taken along the line 3—3 of Fig. 1;

Fig. 4 is a view, partially in cross-section and partially in elevation, of the conveyor mechanism taken along the line 4—4 of 40 Fig. 1;

Fig. 5 is a plan view of a portion of the mechanism shown on the right-hand side of the figure illustrated in Fig. 3;

Fig. 6 is a side view, partially in section, 45 taken along the line 5—5 of Fig. 5, the view of Fig. 6, however, including portions of the mechanism not comprised in Fig. 5;

Fig. 7 is a view similar to Fig. 6 where in several of the members are illustrated as 50 occupying other positions which they may assume during the operation of my machine;

Fig. 8 is a view, partially in elevation and partially in section, of a mechanism incorporated in my machine which is placed in proximity of the stack of articles adjacent to the feeding rolls and serves to preclude more than one article being raised at a time for delivery to the feeding rolls;

Fig. 9 is a transverse view taken along the line 9—9 of Fig. 8;

Fig. 10 is a view, partially in elevation and partially in section, taken along the line 7—7 of Fig. 5;

Fig. 11 is a cross-sectional view showing

the pneumatic connections comprising the members 94, 91 and 97 of my machine and illustrated in Fig. 5;

Fig. 12 is a view, partially in elevation and partially in section, taken along the line 70 12—12 of Fig. 5;

Fig. 13 is a view, partially in elevation and partially in section, of the pneumatic control mechanism and is taken along the line 8—8 of Fig. 3;

Fig. 14 is a view similar to Fig. 13, showing the pneumatic control mechanism of Fig. 13 in a different position;

Fig. 15 is a sectional view taken along the line 15—15 of Fig. 13;

Fig. 16 is a plan view of a portion of the mechanism illustrated in Fig. 1 showing the arrangement of parts by means of which the gripping finger 102 of Figs. 6 and 7 is operated;

Fig. 17 is a view in elevation taken along the line 12—12 of Fig. 16;

Fig. 18 is a view similar to that in Fig. 17 showing the elements comprised in Fig. 17 as occupying changed positions;

Fig. 19 is a view, partially in elevation and partially in section, taken along the line 14—14 of Fig. 18;

Fig. 20 is a cross-sectional view taken along the line 15—15 of Fig. 18;

Fig. 21 is an enlarged view in elevation of a portion of the driving mechanism shown in Fig. 1;

Fig. 22 is a view, partially in elevation and partially in section, taken along the line 22—22 of Fig. 21; and

Figs. 23, 24 and 25 are views taken along the line 23—23 of Fig. 22 and showing three different positions of the elements comprising the automatic means for actuating the 105 conveyor mechanism embodied in my machine.

Referring to Figs. 1 and 3, a machine embodying a form of my invention is mounted upon a base or bed plate 25 and 110 comprises two forward spaced side frames 26 which are bolted to the bed plate 25 and upon which a horizontal table 27 is mounted. A central supporting frame 28 and a rear supporting frame 29 likewise 115 serve to mount and to firmly hold the table 27 in a fixed horizontal position.

The articles to be operated upon by my machine, which may be newspapers, sheets of papers, magazines, etc., represented at 120 73 in Figs. 6 and 7, are disposed upon the upper surface of the table 27 and in contact with transversely spaced conveyor chains 42 that travel in channels 43 which are cut longitudinally in the upper face of 125 the table 27.

First, I will describe the mechanism for delivering the articles 73 to the portion of my machine where each article may be handled separately and automatically.

A forward supporting bracket 30 and a rear supporting bracket 31 of Fig. 1 are positioned vertically on the same side of the table 27, as shown best in Fig. 3. The brackets 30 and 31 provide bushings in which shafts 32 are journalled, each of said brackets supporting at its top and bottom the bushings for the said shafts. These four shafts 32 are disposed at the corners of a rectangle, such as is shown best in Fig. 1. Each shaft 32 extends through, and projects on both sides from, its associated bushing which is formed therein. Two sprocket wheels 33 are severally secured to the two projecting ends of each shaft 32, the inner group of sprocket wheels 33 lying in substantially the same vertical plane and likewise the outer group of sprocket wheels 33. It will thus be observed that two groups of sprocket wheels 33 lie in two spaced parallel and vertical planes, as shown in Fig. 3, while the sprocket wheels of each group are similarly placed at the corners of a rectangle as shown in Fig. 1. Two endless sprocket chains 34 severally engage the peripheries of the two groups of sprocket wheels 33 thus forming two transversely spaced and parallel endless conveyor chains that travel around the peripheries of the two similar rectangles mentioned above.

The sprocket chains 34 are of the usual form of construction and support at spaced intervals groups of fingers 35 that are mounted upon horizontally projecting shafts 36 which extend through corresponding links of the two spaced sprocket chains 34 to which the shafts 36 are secured. The shafts 36 extend transversely over the table 27 and have the fingers 35 severally secured thereto, these fingers being spaced equally from one another upon the shafts 36, if desired.

In Fig. 4 I have shown the construction by means of which the links of the two endless chains 34 are retained in spaced relation from each other and also how the shafts 36 are secured to the two endless sprocket chains 34. The shaft 36 extends through corresponding links of the two spaced sprocket chains 34 and a sleeve 38, through which the shaft 36 projects, is placed intermediate and in abutting engagement with the chains 34 thereby maintaining the chains in spaced relation to each other.

Shoes 39 of Figs. 1 and 4, which are placed exteriorly of, and in contact with, the inner sprocket chain 34 and through which the shafts 36 extend are firmly secured to the shafts by means of pins 39'. The shoes 39 are adapted to slidably engage the upper surfaces of a horizontal angle iron member 44 which extends longitudinally of the table 27, as shown in Fig. 1. The angle iron 44 is bolted to a side frame 45 that likewise extends longitudinally of the table 27. The side frame 45 is secured to the bracket supports 30 and 31 by means of screw 46. The projecting ends of the shafts 36 adjacent to the shoes 39 extend transversely over the table 27 and to these portions of the shafts 36 the fingers 35 are secured by any suitable means. The other ends of the shafts 36 which project through the outer sprocket chain 34 are likewise severally provided with shoes 40 that are firmly secured to the shafts 36 by means of pins 41. The upper faces of the shoes 40 slidably engage the under surface of a horizontal member 47 that extends longitudinally of the table 27 and is bolted to the brackets 30 and 31 by means of bolts 48. It will thus be observed that each of the shafts 36, when travelling along the lower sides of the rectangles formed by the two endless sprocket chains 34, is maintained in a horizontal position by reason of the engagement of the shoes 39 and 40 with the horizontal retaining members 44 and 47.

When the fingers 35 occupy their lowest position, that is, when they are travelling along the lower sides of the rectangular configurations in which the two sprocket chains 34 are arranged, these fingers may be subjected to severe mechanical strains resulting from the weight of the articles 73 which the fingers 35 are adapted to engage and which are located upon the table 27 in order to be conveyed to the feeding mechanism of my machine. As will be hereinafter explained, the articles 73 which are delivered to the feeding mechanism of my machine are transferred thereto by means of the fingers 35. Each of the shafts 36, therefore, when serving to deliver articles to the feeding mechanism, as hereinafter explained, will tend to become displaced from its horizontal position, but this is precluded since each of the shafts 36 is fulcrumed on the angle iron 44 and restrained from movement out of its horizontal position by reason of the sliding engagement between the shoe 40 and the member 47.

Each of the shafts 36 is rotatably mounted in the links comprising the chains 34 and the shoes 39 and 40 are firmly secured to the shafts 36. Likewise the fingers 35 are secured to the shafts 36.

The shafts 36 are maintained in horizontal positions even when they are travelling along the two ends and the upper side of the rectangles formed by the endless sprocket chains 34. Two vertical angle irons 56 of Figs. 1 and 3 which extend along the ends of the rectangles and which are bolted to the supporting brackets 30 and 31 serve to support the sprocket chains 34 since the shoes 39 slidably engage the angle irons 56 as the sprocket chains are travelling around the peripheries of the rectangles which they form. Again, angle iron 49, located at the

top of the rectangle formed by the inner sprocket chain 46 is slidingly engaged by the shoes 39 on its upper face. The horizontal angle iron 49 extends longitudinally 5 of the table 27 and is bolted to the supporting brackets 30 and 31. A longitudinally extending member 50 also bolted to the supporting brackets 30 and 31 is slidingly engaged by the shoes 40 that are secured to 10 the outer sprocket chain 34. When the shafts 36 are travelling along on the upper sides of the rectangles they are maintained in their horizontal positions by means of the shoes 39 being fulcrumed on the upper face 15 of the angle irons 49 and restrained from rocking movement by means of the shoes 40 being held by the member 50. The brackets 51 serve to support the frame-work comprising the rectangles around which the two endless 20 sprocket chains 34 travel and these brackets 51 are bolted to the supporting brackets 30 and 31 by means of bolts 52. Brackets 53, shown in Fig. 3, likewise serve to support the members comprising the 25 rectangles and particularly the longitudinally extending and horizontal member 50 with which the shoes 40 slidingly engage as the two sprocket chains 34 travel along the peripheries of the rectangles. 30 A compression rod 55 extends longitudinally of the table 27 and connects the upper ends of the supporting brackets 30 and 31 in order to maintain the rectangles rigid. As the fingers 35 advance, the articles 33 35 that are to be delivered to the feeding mechanism, it is necessary that the fingers 35, upon being released from contact with the articles, disengage therefrom in such a manner that the fingers will not tear or 40 mutilate the articles. By referring to Fig. 2, it will be seen how this is accomplished. As the shoe 39 disengages from the angle iron 44 at the corner of the rectangle, the weight of the fingers 35, that are secured to 45 the same shaft 36 whereto the shoe 39 is secured, will cause the shoe to assume a new position by reason of the fingers falling into substantially vertical positions as a result of gravity action. As a consequence, the 50 fingers 35 will project downwardly when the shoe 39 disengages from the angle iron 44. At the same time, the shoe 39 is traveling around the sprocket wheel 33 which is disposed at the same corner of the rectangle. 55 When the fingers 35 are pointing vertically downward they will have no tendency to mutilate or disturb the articles which they have conveyed and subsequently released. 60 As the chain 34 travels upwardly, the shoe 39 will abut against the end 57 of the angle iron 56 that is vertically located at the end of the rectangle. As the shoe 39 engages the end 57, as shown by the dotted lines of Fig. 2, the shaft 36 to which the shoe 65 39 is secured will be rotated as the chain 34

continues to travel upwardly. Consequently, the fingers 35 will be forced to such a position that they will extend laterally and upwardly from the end of the rectangle as shown in Fig. 1. Since the relative positions of the shoes 39 and the fingers 35 are fixed, after initial adjustment, the fingers 35 will occupy such positions relative to the shoes 39, that the fingers may readily engage with articles 73 located at the far end of the 70 table 27, as the chains 34, on their travel around the periphery of the rectangles bring the fingers successively into contact with the articles to be delivered to the feeding mechanism. 75

As hereinafter to be explained the travel of the endless chains 34 is brought about by means of a sprocket chain 168 of Fig. 3 that engages a sprocket wheel 168' which is mounted on the end of the shaft 32 upon 80 which those sprocket wheels 33 closely adjacent to the feeding mechanism of my machine are located.

After the papers, magazines or other articles 73 have been delivered to the fore part 90 of the machine by the feeding fingers 35 and the conveyor chains 42, the articles 73 will be engaged by two spaced joggers 58 (Fig. 3) as shown in Figs. 6 and 7. It is, of course, understood that the conveyor chains 42 work 95 in conjunction with the traveling fingers 35, as will later appear, in order that the articles 73 may be carried into proximity to the space provided by the walls 45 and partitions 45'. The joggers 58 periodically tamp 100 the upper exposed edges of the articles 73 thereby forcing the articles to arrange themselves into stacks that engage stops 59 which extend transversely of the table 27 and are secured thereto by means of screws 60. 105

The joggers 58 act in unison and have imparted to them an up-and-down or tamping motion by reason of their being connected to the cam mechanism illustrated in Figs. 5, 6, 7 and 12. Attention is first directed to Fig. 12 wherein a portion of a jogger lever 68 is shown whereto one of the joggers 58 is attached. The jogger lever 68 receives its tamping or up-and-down motion from a cam 61 that is mounted upon a rotatable shaft 115 106 and has a cam guide-way 61' cut there-in. A roller 62 is adapted to travel in the guide-way 61' and serves to impart the proper motion to a cam lever 63, the roller 62 being secured thereto by means of a pin 120 64. The cam lever 63 comprises an extending guiding-rod portion 65' which is embraced by a helical spring element 65. The helical spring element 65, which serves as a compression member, is interposed between 125 the portion of the cam lever 63 that is immediately adjacent to the guiding-rod 65' and a block member 72 that is slidably mounted upon the guiding-rod 65'. The block 72 is secured at the outer end of the 130

guide-rod portion 65' by means of the nuts 72'. An arm 66 is pivotally secured to the block 72 and is adapted to slide therewith as the block 72 compresses the spring 65. The 5 arm 66 is secured to a jogger shaft 67 which is journaled in the side frame 26 and is oscillated about its axis by reason of the motion imparted thereto by the arm 66, as shown in Fig. 5. The jogger arm 68 is bolted 10 to the jogger shaft 67 by means of a bolt 69. The jogger arm 68, as shown in Figs. 6 and 7, has bolted to its outer extremity a jogger support 69' which is secured thereto by means of a bolt 70. The jogger 58 is 15 mounted upon the jogger support 69' and an adjusting bolt 71, which extends through the jogger arm 68 and an arcuate slot formed in the jogger support 69' permits the adjusting of the relative position of the jogger 58.

20 By referring to Fig. 3 in conjunction with Fig. 5 it will be observed that the joggers 58 are mounted at spaced intervals upon the rotatable shaft 67 to which they are secured.

The force imparted to the joggers 58 by 25 means of the cam 61 is cushioned by the compression spring 65 of Fig. 12. The spring 65 therefore protects the exposed edges of the articles 73 from being tamped too severely by means of non-resilient and intense 30 blows that would otherwise result from the tamping action of the joggers 58 if the compression spring 65 did not serve to relieve the tamping blows from unduly extreme pressures.

35 When the articles 73 have been tamped so that they occupy the positions illustrated in Figs. 6 and 7, the upper article 73 is brought into contact with lifters 74, (Fig. 3) which are spaced transversely of the table 27 and are severally provided with vacuum-cup members 75. The vacuum-cup members 75 are preferably made of a flexible material, such as rubber, which ensures an air-tight 40 suction contact between the lifters 74 and the articles 73 as they successively reach the upper and exposed position at the top of the stack where each article, in turn, is brought into direct contact with the vacuum-cups 75.

45 As will be hereinafter explained, each of the lifters 74 is a hollow member and communicates directly with its associated vacuum-cup 75, the whole being evacuated as will appear later. When the vacuum cups 75 engage the topmost article 73 and then are evacuated, the article thus engaged will be raised by reason of the resulting suction as the lifters 74 are raised.

50 The up-and-down movement of the lifters 74, which operate in unison, is transmitted to them through a cam mechanism which is 60 illustrated in Figs. 5, 10 and 11. Attention is directed to the structure shown in Fig. 10 wherein the lifter 74, shown in dotted lines, 65 occupies its lowermost position. The lifter

74 attains its lowest position when a cam-roller 85 occupies a position at the center of the cusp formed in a cam-way 84 with which the cam 83 is provided. The cam 83 is rotatably mounted upon the shaft 106. 70 The cam roller 85 is attached by means of a pin 85' to a cam-lever 86 and, in conjunction with the cam-way 84, serves to impart an oscillating motion to the cam-lever 86. The cam-lever 86 is provided with a cam-lever 75 rod 88 having a shoulder 87 formed thereupon. Extending from the shoulder 87 is a guide-rod 88' which extends through an opening formed in a pin 89 (Figs. 5 and 11). A compression spring 101 embraces the outer 80 projecting end of the guide-rod 88' and is held in position and in compression by means of nuts 101' that are threaded to the extreme end of the guide-rod 88'. The pin 89 is firmly secured to a rocker arm 90 which 85 is rotated by means of the motion imparted thereto by the rocking action of the cam lever 86. As illustrated in Fig. 11, the rocker arm 90 is keyed to a rotatable tubular member 91 by means of a key 96; the tubular member 91 extending laterally from the rocker arm 90 as shown.

90 By reason of the mechanical connection made between the rocker arm 90 and the tubular member 91 through the medium of the key 96, the tubular member 91 is rotated in unison with the rocking of the rocker arm 90. The tubular member 91 projects through the support 26 into which it is journaled. A 95 laterally extending tubular portion 92 is formed on the tubular member 91 and to this portion 92 a tubular member 97 is secured.

100 By referring to Figs. 6, 7 and 10 it will be noted that the lifters 74 are secured to the tubular extension 97. Moreover, the hollow members 74 communicate with the tubular extension 97 which, in turn, communicates through the tubular portion 92 with the tubular member 91 of Fig. 11. Again, the lifters 74, by means of their mechanical connection with the rocker arm 90, which mechanical connection is furnished through the foregoing tubular members, move upwardly 105 and downwardly as the rocker arm 90 is oscillated by the cam 83. The air in the tubular members 97, 92 and 91, as well as the air in the lifters 74 and the vacuum cups 75 is exhausted through a pipe 94 which is connected through a valve mechanism, to be hereinafter described, to any suitable vacuum-pipe. The pump 94 is provided with an elbow 94' that is threaded into a stationary 110

115 non-rotatable ferrule 95 which, in turn, is socketed in the tubular member 91 as shown particularly in Fig. 11. A suitable packing 98 which is held in position by means of a collar 99 that is secured to the rocker arm 90 by means of screws 100, serves to main- 120 125 130

tain an airtight connection between the stationary pipe 94, the stationary ferrule 95 and the rotatable tubular member 91.

The lifters 74 which simultaneously engage the topmost article 73 at several spaced points serve to lift the article 73 as shown in Fig. 7 so that it may be delivered to feeder rollers 104. When the topmost article has been brought to a proper position by 10 the lifters 74 the outer edge of the lifted article 73 is grasped between a finger 102 and a cushion member 103, both of which are mounted upon the rotatable feeder roller 104. As soon as the article 73 has been 15 grasped by the finger 102 it is necessary that the lifters 74 release the articles 73. This release is effected by admitting air into the lifters 74 which air is admitted through the pipe 94 and the tubular members associated 20 therewith. It will be seen, therefore, that the lifters 74 should engage the topmost article 73 at the proper time, lift it upwardly and then release it in a suitable time interval thereafter. The mechanism by which 25 the lifters 74 are alternately evacuated and supplied with air, in proper sequence and at the proper time intervals, is illustrated in Figs. 13, 14 and 15 to which attention is now directed.

30 A cam 107 that is keyed to a shaft 113 (Fig. 3) is provided with a cam-way 107' that is traversed by a roller 121. The roller 121 is connected by a pin 122 to a regulating plate 108. The regulating plate 108 is provided with a laterally formed recess or chamber 109 which is adapted to bridge either a chamber 110 and a chamber 111 simultaneously in order to establish communication therebetween, or to bridge the chamber 110 40 and a chamber 114 simultaneously for the same purpose. The chambers 110, 111 and 114 are formed in a block member 112 that is secured by means of bolts 112' to a portion of the support 26. The chambers 110, 45 111 and 114 do not communicate with one another except through the agency of the chamber 109. The chamber 110 communicates directly with the pipe 94 which, in turn, is connected to all of the vacuum cup lifters 50 74. The chamber 111 is connected to a pipe 93 that extends to a vacuum pump or any other suitable evacuating mechanism. The chamber 114 is provided with a port hole 115 which communicates with the outer air. The 55 regulating plate 108 is pivoted to a stub shaft 116 that extends through the frame 26 and is secured thereto by means of a nut 117. A compression spring 118 is interposed between the regulating plate 108 and a collar 119 which is secured to the end of the stub shaft 116 by a screw 120. Thus the spring 118 serves to press the regulating plate 60 against the adjacent and coacting face of the block member 112 thereby ensuring a hermetically sealed sliding contact between the

block member 112 and the adjacent face of the regulating plate 108. When the regulating plate 108 occupies the position shown in Figs. 13 and 15, the chambers 110 and 111 are in direct communication with each other 70 through the chamber 109. As a consequence, the pipe 94 and its associated members are being evacuated through the pipe 93.

The cam 107 is so timed that when the lifters 74 are in contact with the topmost 75 article 73, the regulating plate 108 occupies the position shown in Fig. 13, thereby causing the lifters 74 and their associate vacuum cups 75 to be evacuated so as to hold the engaged article 73 in close contact with the 80 lifters in order to deliver the article to the feeding rolls. When the lifters 74 occupy the position as shown in Fig. 6, the regulating plate 108 occupies the position shown in Fig. 13. After the engaged article 73 85 has been lifted up and fed to the feed rollers 104, the lifters 74 are permitted to disengage from the article 73 by reason of the regulating plate 108 having, by this time, assumed the position shown in Fig. 14. In 90 this instance, the chamber 109 formed in the regulating plate 108 affords direct communication between the chambers 114 and 110. The evacuating pipe 93 having thus been disconnected from the pipe 94, which is now in 95 direct communication with the outer air through the port hole 115, permits the lifters 74 to disengage from the lifted article 73.

In order to preclude more than one article 73 being raised at the same time by the lifters 74, a separating knife 75^b of Figs. 8 and 9 is provided. Referring to these figures, it will be observed that the separating knife 75^b is mounted upon a bracket 76 which is pivotally secured by means of a bolt 78 to a 100 support 77 that in turn is bolted to the side wall 45 by means of a bolt 79. The elevation of the separating knife 75 may be adjusted by means of the bolt 79. The spring 80 secured to a support 81 exerts a downward pressure upon the pivoted arm 76 and thus restrains the separating knife 75^b from moving horizontally unless the arm 76 is moved manually. The support 81 is likewise secured to the side frame 45 by means 105 of screws 82. The articles 73, as hereinbefore explained, are tamped by means of the joggers 58 so that they are brought into contact with the stops 59. The level at which the stack of articles 73 is maintained is controlled, as will be explained below. As the articles 73 are lifted from the stack in which they are comprised, the separating knife 75^b scrapes on the exposed edge of the articles 110 and thus precludes more than one article 73 115 being delivered at the same time.

When the lifters 74 have engaged the article 73 at the top of the stack and raised it to the proper position an edge of the article 73 120 is grasped between a finger 102 and a cushion 125 130

member 103 as will be described below. After the article 73 has been engaged by the finger 102, the lifter 74 will release the article by reason of air having been admitted 5 into the tubular member 97 by the timing mechanism illustrated in Figs. 13, 14, and 15 and described in connection therewith. The article 73 will now be advanced by reason 10 of the rotation of the feed rollers 104 which will cause the article 73 to assume the position shown by the dotted lines 73^a of Fig. 7, since the finger 102 and the associated cushion 103 revolve with the feed rollers 104 which are secured on the shaft 106.

15 The mechanism for rotating the finger 102 from its open position which is shown in Fig. 6 to the position where the finger 102 holds the paper or article 73 in contact with the cushion 103, as shown in Fig. 7, is illustrated in details in Figs. 16, 17, 18, 19 and 20. Reference may first be had to Fig. 16 in which a stationary cam member 123 is bolted to a projection 124 formed on the frame 26 by means of bolts 125. As shown 25 in Figs. 17, 18 and 19 the projection 124 is provided with elongated slots 126 through which the bolts 125 project so that the position of the stationary cam 123 may be properly adjusted. The feed rollers 104 are secured to the shaft 106 and are rotated thereby. A gear segment 127 extends from a boss 127' and immediately adjacent thereto an arm 128 extends from a boss 128', said bosses being secured to a feed roller 104 by 30 means of a pivot bolt 129. A roller 130 projects from the arm 128 to which it is rotatably secured by means of a pin 131. The roller 130 travels in a cam-way 132 which is cut in the exposed face of the stationary cam 123.

35 The arm 128 is provided at its ends with a bifurcated portion forming fingers 133 shown in Figs. 16, 17, 18 and 20, which embrace a lug 134 that is integral with the gear segment 127. The lug 134 extends between the fingers 133 and is mechanically connected thereto by means of a spiral spring 135 which is interposed as shown particularly in Fig. 20. The purpose of the spiral spring 40 135 will be hereinafter explained.

When the feed rollers 104 revolve the gear segment 127 and the arm 128 will revolve likewise inasmuch as these two members are secured to the feed rollers 104. Moreover, 45 since the cam 123 remains stationary as the feed rollers 104 revolve, the cam roller 130 which is secured to the arm 128, will also impart a corresponding movement to the gear segment inasmuch as the gear segment 127 is resiliently connected to the arm 128 by means of the fingers 133 and the interposed spiral spring 135 of Fig. 20. Consequently, 50 the gear segment 127 will move in accordance with the travel of the roller 130 in the cam-way 132.

By referring to Figs. 17 and 18 it will be noted that the gear segment 127 is provided with gear teeth 136 which are adapted to mesh with the pinion 137 that is keyed by means of a key 138 to the shaft 105. As described in connection with Figs. 6, 7 and 16, the finger 102 is firmly secured to the shaft 105 which in turn has a rotary motion imparted to it when the gear teeth 136 of the gear segment 127 engage the pinion 137. 75 In Fig. 17, the finger 102 occupies its open position and when in this position the relative positions of the gear segment 127 and the pinion 136 are as shown. When the finger 102 occupies this open position, the lifters 74 of Figs. 6 and 7 are in contact with the article to be lifted and have not, as yet, been disengaged therefrom.

In Fig. 18 the finger 102 is shown in its closed position wherein it is holding the article 73 in contact with the cushion 103 with which the finger 102 cooperates to mechanically deliver the article 73 to the feed rollers 104. When the finger 102 occupies this closed position, the shaft 105 has been rotated from the position that it occupies in Fig. 17, by reason of the movement of the gear segment 127 which movement is effected by the roller 130 traveling in the cam-way 132. The finger 102, when grasping the article 73 as shown in Fig. 18 resiliently presses against the cushion 103 as a result of the interposed spiral spring 135 through which movement to the gear segment 127 is imparted.

It will be observed in Fig. 18 that the gear segment 127 occupies an extreme position by reason of the location of the cam roller 130 in the cam-way 132. Further rotation of the feed rollers 104 will force the cam roller 105 130 to travel downwardly in the cam-way 132 and thereby effect rotation of the pinion 130 in a counterclockwise direction to cause the finger 102 to release the article 73. By this time, the article 73 has been mechanically delivered to the feed rollers and, as a consequence, the release of article 73 by the finger 102 is properly timed so that the article may automatically pass without interruption through the feed rollers 104. The cam 110 roller 130 in this portion of its travel imparts a motion to the gear segment 127 that is the reverse of the motion imparted when the cam roller is traveling in that part of the cam-way 132 to effect closure of the finger 102.

The article 73 having been released from engagement between the finger 102 and the cushion 103 is now gripped between rollers 140 and the serrated surfaces 139 formed on the feed rollers 104. The article 73 will now assume the position shown by the dotted lines 73^a in Fig. 7. As soon as the article 73 is interposed between the feed rollers 104 and the rollers 140, the finger 102 on 130

further rotation of the feed rollers 104 will assume the position shown by the dotted line 102^a of Fig. 7. A guide-way 141 permits the article 73 to slide from the feed rollers 5 and will direct the movement of the delivered articles as desired.

Referring now to Figs. 6, 7 and 21 the feed rollers 140 are mounted upon a rotatable shaft 142 (Fig. 3) the ends of which are 10 journaled in floating bearing blocks 143 that are permitted to move upwardly and downwardly by reason of guide-ways cut therein which are slidably engaged by projections 144 which are integrally formed on 15 the frame 26. The bearing blocks 143 extend through openings formed in the frame 26 and are retained in position by means of the aforesaid projections 144.

Compression springs 145 are inserted between the bearing blocks 143 and surfaces 146 which form the bottom of the openings in the frame 26 that contain the bearing blocks 143. The pressures exerted by the springs 145 firmly compress the rollers 140 25 against the serrated surfaces 139 of the feed rollers 104 thereby ensuring that the articles 73 as they pass through the feed rollers, will be firmly gripped. The pressures exerted by the springs 145 upon the floating 30 bearing blocks 143 may be regulated by means of bolts 147 and lock-nuts 148, said bolts engaging the bearing blocks 143 and extending through the frame 26.

From the foregoing description of the 35 method of delivering the articles 73 severally to the feed rollers 104 and 140, it will be apparent that the articles could not be delivered at a sufficiently high rate to require the continuous operation of the conveyor chains 42 and the delivery fingers 35 of Figs. 1 and 3. In the present instance I have, therefore, provided means for intermittently operating the conveyor chains 42 and the delivery fingers 35 in order that a 40 proper supply of articles 73 may be delivered to the lifters 74. The operation of the conveyor chains 42 and the delivery fingers 35 is regulated by the height of the stack comprising the articles 73 that rests 45 against the stops 59 of Figs. 6 and 7. In Fig. 6, a finger 149 secured to a rotatable shaft 150 by means of a bolt 151 engages the top of the stack of articles 73 and the finger 149 is the instrument by means of which I 50 control the intermittent operation of the conveyor or delivery mechanism to the articles 73 to the stops 59.

Since the finger 149 engages the top of the stack of articles 73, it is obvious that the 60 finger 149 must be lifted upwardly to release the topmost article 73 as it is engaged and raised by the lifters 74. In order to lift the finger 149 at the proper time so that the topmost article may be firmly grasped 65 without opposition by the lifters 74, the fin-

ger 149 is actuated by the jogger cam 61, as shown in Fig. 12. In this figure it will be observed that the shaft 150 to which the finger 149 is firmly secured is rotated by means of an arm 155 that is secured at its 70 upper end to a block 154 (Fig. 5) by means of a stud 156 and a nut 157. The block 154 is slidably mounted upon an extension 152' formed on the rod 152 that is connected to the cam lever 63 by means of a bolt 153. 75 The block 154 abuts against a shoulder 159 formed on the rod 152 and a spring 158 embraces the extension 152' and controls the pressure exerted by the finger 149 from the stack of articles 73. The spring 158 will be 80 compressed when the height of the stack of articles 73 is such that the finger 149 cannot travel freely the full distance downwardly as the cam 61 rotates. When the lifters 74 engage the topmost article 73 and raise it 85 upwardly the finger 149 will be actuated by the jogger cam 61, as explained above, and will be raised at the proper time so that movement of the topmost article 73 will not be hindered. The actuation of the finger 90 95 149 is ensured by reason of the positive engagement between the shoulder 159 formed on the rod 152 and the slidable block 154 that is firmly pressed thereagainst.

When the level of the stack of articles 73 falls below a certain predetermined height the finger 149, by reason of its movement downwardly as the stack decreases, will cause a tripping finger 160, shown in Fig. 21, to engage a projection 161 formed on a 100 latch 162. The finger 149 is firmly secured to the shaft 150 which extends through the frame 26 and on the outer end of which the tripping finger 160 is secured. The latch 162 is secured to a stub shaft 163 which like- 105 wise projects laterally from the frame 26. When the projection 161 is sufficiently depressed by the tripping finger 160, the latch 162 will disengage itself from a projection 164 that is formed on a cam member 184, as 110 will hereinafter appear. A tension spring element 169, having one of its ends secured to the frame 26 and the other embracing a pin 190 that extends laterally from the projection 164 to which the pin is secured, will 115 pull the projection 164 downwardly as it is released by the latch 162. Since the projection 164 is a part of a cam 184 that is rotatably mounted upon a shaft 167, the cam 184 will be rotated by the action of the 120 spring 169. When the cam 184 is moved by the spring 169 by reason of the disengagement of the latch 162 from the projection 164, a pawl 165 will engage a ratchet wheel 166 that is keyed to the shaft 167 as shown 125 in Fig. 23. The pawl 165 has an oscillatory motion imparted to it and, as a consequence, it will engage the teeth on the ratchet wheel 166 in succession thereby rotating the shaft 167 to which sprocket wheels 168 of Figs. 130

6 and 7 are secured. The sprocket wheels 168 actuate the conveyor chains 42 that serve as a means for delivering the articles 73 to the feed rollers 104 and 140.

5 It will also be observed by referring to the right-hand side of Fig. 3 that a shaft 170 is also rotated by the shaft 167, the former being provided with a gear 171 that meshes with a gear 172 keyed on the end of 10 the shaft 167. A sprocket wheel 169 is mounted on the shaft 170 and the chain 168 passes over the sprocket wheel 169 as well as the sprocket wheel 168' that is mounted on an extension of the shaft 32 which shaft 15 is located immediately adjacent to the feeding mechanism. The sprocket chains 34 forming the rectangular configuration, shown in Fig. 1, are rotated by reason of the sprocket chain 168 and, as a result, the 20 delivery fingers 35 will thus serve to deliver the articles 73 to the feeding mechanism, as hereinbefore explained.

Attention is now directed to Figs. 22, 23, 25 and 24 and 25 in connection with the mechanism illustrated in Fig. 21. The gear wheel 175, as will be hereinafter described, serves to transmit power through a link 179 that is pivotally secured to it by means of a bolt 180. The other end of the link 179 is pivotally secured to a rocker arm 181 by means 30 of a bolt 182. As shown particularly in Fig. 22, the rocker arm 181 is provided with an integral extension 181' to which the pawl 165 is pivotally secured by means of a bolt 183. A compression spring 186 is contained 35 in a recess formed in the extension 181' and serves to press the pawl 165 into positive sliding engagement with the ratchet wheel 166. As the gear 175 rotates the pawl 40 165 is given an oscillatory or back-and-forth motion by reason of the link mechanism comprising the link members 179, 181 and 181'. A roller 185 is placed immediately adjacent to the pawl 165 and is rotatably 45 mounted on the extension 181' so that as the roller 185 is moved the pawl 165 will likewise move. The roller 185 is so positioned that it is adapted to be engaged by the cam 184. The cam 184 is rotatably 50 mounted upon the shaft 167 as shown in Figs. 23, 24 and 25, by embracing a sleeve 187 that is formed integral with the ratchet wheel 166. The ratchet wheel 166 is keyed to the shaft 167 by means of a key 188 that 55 engages the sleeve 187.

The cam 184, in addition to being provided with the extension 164 is also provided with a projection 184'. When the latch 162 is held in engagement with the 60 projection 164, as shown in Figs. 23 and 24 and which condition obtains when the stack of articles 73 has not fallen below a certain predetermined level, the projection 184' of the cam 184 occupies the position as shown. 65 The pawl 165 in Fig. 24 is disengaged from

the ratchet wheel 166 by reason of the projection 184' of the cam elevating the roller 185 that is secured to the pawl 165. In this position, the pawl 165 is disengaged from the ratchet wheel 166 and, as a consequence, 70 cannot rotate the shaft 167 which controls the feeding of the articles 73 to the feed rollers as hereinbefore described. As the gear wheel 175 continues to rotate the pawl 165 will periodically assume the positions 75 shown in Figs. 23 and 24. While the pawl 165 is shown in engagement with the ratchet wheel 166 in Fig. 23 the pawl has reached the end of its travel and consequently does not rotate the ratchet wheel. When the pawl 80 assumes the position as shown in Fig. 24 the roller 185, having been elevated by the cam 184, precludes the pawl 165 from operatively engaging with the ratchet wheel 166.

As long as the latch 162 holds the projection 164 upwardly, the cam 184 precludes the pawl 165 from rotating the ratchet wheel 166 as the pawl oscillates back and forth by means of the continued rotation of the gear wheel 175. The mechanism will 85 occupy the positions shown in Figs. 23 and 24 as long as the finger 149 has not fallen to such a level as will cause the latch 162 to be disengaged from the projection 164 formed on the cam 184. 90

When the stack of articles 73 falls below a certain level, the finger 149 will be substantially depressed and cause the tripping finger 160 to engage the projection 161 secured to the latch 162. As a consequence, 95 the latch 162 will become disengaged from the projection 164. The spring 169 will cause the cam 184 to assume the position shown in Fig. 25. When the cam occupies this position, the roller 185 which is adapted, 100 when in contact with the cam 184, to hold the pawl 165 from operative engagement with the ratchet wheel 166, permits the pawl 165 to successively engage the several teeth formed on the ratchet wheel 166 and 105 the pawl is given a rotatable oscillatory motion through the continuous rotating of the gear wheel 175.

It will be observed by referring to Figs. 22 and 25 that the cam 184 is periodically 110 restored to the position indicated in Figs. 23 and 24 by reason of the continuous rocking of the lever 181 which is provided with an integrally formed extension 189 that abuts against the pin 190 secured to the 115 cam extension 164. As the lever 181 is rocked the cam 184 will be likewise rocked thereby extending the spring element 169. If the latch 162 is restored to its normal position by being released from engagement 120 with the rocker finger 160, the latch will then engage the cam projection 164 and hold the cam in the positions shown in Figs. 23 and 24. However, if the latch 162 is still held in disengaged position as a result 125 130

of the continued depression in the finger 149, the cam 184 will not be held in the position shown in Figs. 23 and 24 and, as a consequence, the pawl 165 will continue to turn 5 the ratchet wheel 166 thereby continuing the feeding of the articles 73 to the stops 59.

Referring to Fig. 1 the motive power for 10 operating my machine is derived from a source of power represented by an electric motor 173 having a pinion 174 secured to its shaft which pinion meshes with an idler gear wheel 174' that, in turn, meshes with the gear wheel 175 of Fig. 21. Power is transmitted from the gear wheel 174 to the shaft 15 106 to which the feed rollers 104 are secured by means of two interposed idler gears 176 and 177 that transmit power to gear 178 that is keyed to the shaft 106.

When the motor 173 is at a standstill the 20 machine may be manually operated by means of a hand lever 191 (Fig. 21) which slidingly rotates upon a shaft 191'. A ratchet wheel 193 and a gear 194 are secured to the shaft 191' in any suitable manner. 25 The pawl 192 is secured to the lever 191 and is adapted to engage the teeth of the ratchet wheel 193. Thus the ratchet wheel 193 is turned by reason of its engagement with the pawl 192. The gear 194 will be likewise rotated which in turn meshes with the gear 30 wheel 175. By manually rotating the gear wheel 175 the entire machine may be operated.

Having thus described my invention, what 35 I claim as new and desire to secure by Letters Patent, is:

1. A machine of the character described comprising means for feeding articles, means for supplying a plurality of articles toward 40 said feeding means, means for transferring forwardly said articles one by one to said feeding means, and means for properly arranging in piles the supplied articles adjacent to said feeding means to be acted upon 45 by said transferring means.

2. A machine of the character described comprising article feeding means, article-grasping members for feeding the articles individually, means for lifting said articles 50 one by one from a mass of the same into juxtaposition with said grasping members, means operating upon said mass of articles to properly position the same adjacent said lifting means, means for supplying articles 55 in bulk adjacent to and to the rear of said lifting means, and means governed by said mass of articles adjacent to said lifting means to control said article-supply means.

3. A machine of the character described 60 comprising continuously-operating article-feeding means, grasping members whereby articles may be individually fed, intermittently operated conveying means for supplying articles in bulk adjacent to said feeding 65 means, means for urging said articles in bulk

forwardly towards said article feeding means, means for lifting said articles one by one into juxtaposition with said grasping members, and means for causing the operation of said conveying means when the articles adjacent 70 said feeding means lack a predetermined measure.

4. A machine of the character described comprising continuously-operating article-feeding means, grasping members whereby 75 articles may be individually fed thereto, intermittently or continuously operating conveying means for supplying articles in bulk adjacent said feeding means, means for lifting said articles one by one into juxtaposition with said grasping members, means for causing the operation of said conveying means when the articles adjacent 80 said feeding means lack a predetermined measure, and means for tamping said plurality of articles into proper arrangement for operation 85 thereupon of said lifting means.

5. A machine of the character described comprising means for feeding articles, conveying means for supplying a plurality of 90 articles adjacent said feeding means, means for lifting said articles one by one into juxtaposition with said article feeding means, a finger the position of which controls the operation of said conveying means resting 95 upon said articles, and means for lifting said finger clear of said articles as said lifting means operates.

6. A machine of the character described comprising means for feeding sheet-like articles one by one, conveying means for supplying a mass of said articles adjacent said feeding means, means comprising a suction cup for lifting said articles one by one into proximity with said feeding means, means 100 for rendering said suction cup ineffective 105 while said feeding means are operating upon one of said articles, and means for properly arranging said articles to be acted upon by said cup.

7. A machine of the character described comprising means for feeding sheet-like articles one by one, conveying means for supplying a mass of said articles adjacent said feeding means, means for piling said articles 115 substantially parallel to the direction of feed, and means for governing the operation of said conveying means in accordance with the thickness of the pile of articles whereby the same may be supplied in correct quantity.

8. A machine of the character described comprising means for feeding sheet-like articles one by one, conveying means for supplying a mass of said articles adjacent said feeding means, means for piling said articles 120 substantially parallel to the direction of feed, means comprising a spring-pressed finger for governing the operation of said conveying means in accordance with the thickness of the pile of articles whereby the 125 130

- same may be supplied in correct quantity, means comprising a suction cup for engaging said articles, and means for simultaneously lifting said cup and said finger where-
 5 by said articles may be placed in juxtaposi-
 tion with said feeding means.
9. A machine of the character described comprising means for conveying a plurality of sheet-like articles to a predetermined
 10 point, means for grasping said articles and feeding them one by one, means comprising a suction cup for lifting said articles into juxtaposition with said grasping means, means comprising a tamping mechanism for
 15 arranging said articles to be engaged by said suction cup, means comprising a finger pressed against said articles to control said conveying means, means for simultaneously lifting said cup and said finger whereby said
 20 articles are transferred to said feeding means, and means for rendering said suction cup ineffective while said articles are being drawn thereby through said feeding means.
- 25 10. In a machine of the character de-
 scribed, the combination with mechanism for supplying articles to be fed in bulk, means for arranging said articles adjacent to a feeding mechanism, and means for feeding
 30 said articles individually to said feeding mechanism, of a feeding mechanism continually operating to eject said articles from the machine, and means for intermittently controlling said first mechanism that supplies
 35 the articles in bulk.
11. A machine of the character described comprising a feeding mechanism, means for supplying a plurality of articles adjacent thereto, means for arranging said articles in
 40 proper position, and additional means controlled by the articles adjacent to said feeding mechanism for intermittently operating said first means for supplying the articles adjacent said feeding mechanism.
- 45 12. A machine of the character described comprising a feeding mechanism to eject articles one by one therefrom continuously, lifting means to engage said articles prior to their delivery to said feeding mechanism,
 50 grasping means to engage said articles subsequent to their engagement with said lifting means in order to positively deliver each article forwardly in turn to said feeding mechanism, and means controlled by the
 55 supply of said articles adjacent to said feeding mechanism for automatically delivering articles in bulk adjacent to said feeding mechanism and in operative relation to said lifting means.
- 60 13. A machine of the character described comprising a feeding mechanism for delivering articles therefrom without interruption, a conveyor mechanism for supplying articles in bulk adjacent to said feeding mechanism,
 65 means for arranging said articles adjacent to said feeding mechanism, means for lifting said articles after being thus arranged, means for grasping said articles to deliver them positively to said feeding mechanism, and means controlled by the quantity of ar-
 70 ranged articles adjacent to said feeding mechanism for intermittently and automatically operating said conveyor mechanism.
14. A machine of the character described comprising article feeding means, means for supplying articles adjacent thereto in bulk and to the rear of said article feeding means, and means for continuously operating on said articles in bulk for urging them forwardly towards said article feeding means.
15. A machine of the character described comprising article feeding means, means for supplying articles thereto in bulk and to the rear of said article feeding means, means for continuously operating on said articles in bulk for urging them forwardly towards said article feeding means, and means governed by the number of articles adjacent and to the rear of said feeding means for controlling the article supply means whereby the supply of said articles in bulk may be maintained in excess of a minimum quantity.
16. A machine of the character described comprising a table whereupon articles may be deposited in bulk, conveying means built in said table and upon which said articles may rest, spaced and downwardly extending members superimposed upon said conveying means and adapted to engage said articles in bulk from above, and means for moving said downwardly extending members simultaneously with said conveying means thereby transporting articles in bulk longitudinally of said table.
17. A machine of the character described comprising a table whereupon articles may be deposited in bulk, conveying means built in said table and upon which said articles may rest, spaced and downwardly extending members superimposed upon said conveying means and adapted to engage said articles in bulk from above, and intermittently operable means for moving said downwardly extending members in conjunction with said conveying means thereby transporting said articles in bulk adjacent to and at the rear of article feeding means.
18. In a machine of the character described, the combination with continuously operable article feeding means, of a table whereupon articles may be deposited in bulk, conveying means built in said table and upon which said articles may rest, spaced and downwardly extending members superimposed upon said conveying means and adapted to engage said articles in bulk from above, and means governed by the number of said articles adjacent to said article feeding means for automatically actuating said conveying means and said downwardly extending members.

19. In a machine of the character described, the combination with a surface adapted to receive articles to be moved longitudinally thereof, of a conveying mechanism spanning a portion of said surface which comprises an endless chain, a plurality of spaced and downwardly extending members secured to said chain and adapted to engage articles in bulk that may be deposited on said surface, and means for actuating said chain thereby moving said downwardly extending members and said articles in bulk longitudinally of said surface.
20. In a machine of the character described, the combination with a surface adapted to receive articles in bulk, of a conveying mechanism located above said surface for moving said articles in bulk which comprises spaced rotatable members, an endless chain engaging said members, a plurality of spaced shoes attached to said chain and movable therewith, downwardly extending fingers severally secured to said shoes and adapted to engage said articles in bulk, said shoes permitting said fingers to extend vertically downwardly at the end of their forward travel, and automatic means for actuating said endless chain.
21. A machine of the character described comprising article feeding means, conveying means for supplying articles in bulk adjacent to said article feeding means, means for transferring said article one by one in juxtaposition to said article feeding means, and a continuously operating jogger for arranging said articles in a pile immediately adjacent to said article feeding means whereby the articles may be acted upon by said transferring means.
22. A machine of the character described comprising article feeding means, grasping members for feeding articles individually thereto, means for transferring said articles one by one into juxtaposition with said grasping members, a continuously operable jogger acting upon articles for arranging them adjacent to said article feeding means, conveying mechanism for supplying articles in bulk at the rear of said receiving means, and automatic means controlled by the mass of articles adjacent to said article feeding means for actuating said conveying means.
23. A machine of the character described comprising continuously operating article feeding means, grasping members associated therewith for feeding articles separately thereto, intermittently operated conveying means for supplying articles in bulk adjacent to the rear of said article feeding means, means for lifting articles individually into juxtaposition to said grasping members, and means controlled by the quantity of articles adjacent to said article feeding means for automatically effecting the operation of said conveying means.
24. A machine of the character described comprising continuously operating article feeding means, grasping members associated therewith for engaging articles one by one, conveying mechanism for supplying articles in bulk adjacent to said article feeding means, means for lifting articles one by one into juxtaposition to said grasping members, means for arranging a plurality of articles in a pile adjacent to said article feeding means, and a member engaging said pile of articles for automatically actuating said conveying means when said pile lacks a predetermined measure of articles.
25. A machine of the character described comprising article feeding means, conveying means for supplying articles in bulk adjacent to said feeding means, means for regularly arranging said articles in a pile adjacent to said article feeding means, a spring-pressed finger governing the operation of said conveying means and adapted to engage said pile of articles adjacent to said article feeding means, an oscillating suction cup for lifting articles one by one from said pile, and means for simultaneously lifting said cup and said finger so that articles may be placed one by one in juxtaposition to said feeding means.
26. A machine of the character described comprising article feeding means, a conveying mechanism for supplying articles in bulk adjacent to said article feeding means, a continuously operable device for arranging said articles in proper position relatively to said article feeding means, and automatic means controlled by a mass of arranged articles for operating said conveying means in order to retain a fixed supply of articles adjacent to said article feeding means.

In witness whereof, I have hereunto subscribed my name.

SIMON COOPER.
